UNITED STATES PATENT OFFICE.

JAMES H. FOOTE, OF CINCINNATI, OHIO.

WEATHER STRIP.

Application filed February 27, 1924. Serial No. 695,563.

My invention relates to improvements in weatherstrip. One of its objects is to provide an improved all metal weatherstrip. Another object is to provide an improved 5 weatherstrip having a more uniform resilient tension over a wide range of adjustments, whereby a long period of uniform resiliency in use is insured. Another object is to provide an improved form of 10 metal weatherstrip whereby improved and continuous close contact is maintained the full length of the joint. Another object is to provide normally for a double sliding or surface contact at the joint. Another object is to provide a weatherstrip better 15 adapted to exclude wind and water. My invention also comprises certain details of form and combination of components, all of which will be fully set forth in the description of the accompanying drawings, in which; 20

Fig. 1, is a perspective view of a section of metal weatherstrip embodying my invention.

Fig. 2, is a similar view illustrating a modification of Fig. 1.

Fig. 3, is a horizontal sectional detail through one side of a window frame and sash illustrating the application of my invention, Fig. 1, to a loose window joint.

Fig. 4, is a view similar to Fig. 3, illustrating the application of the strip Fig. 1 to a close joint.

Fig. 5, is a horizontal sectional detail 35 through one side of a door frame and door illustrating the application of the strip Fig. 1 to a door joint.

Fig. 6, is a view similar to Fig. 3, illustrating the application of a strip Fig. 2, 40 to a loose window joint.

Fig. 7, is a view similar to Fig. 6, illustrating the application of a strip Fig. 2, to a close window joint.

Fig. 8, is a view similar to Fig. 6, illustrating the application of a strip Fig. 2, 45 to a moderately loose joint.

Fig. 9, is a perspective detail of a section of strip showing a latch or bolt recess.

The accompanying drawings illustrate the 50 preferred embodiments of my invention. As illustrated in Figs. 1, 3, 4, and 5, the weatherstrip is constructed of resilient sheet metal and comprises a plane central section 15, at one end of which the metal is 55 bent at an angle to section 15 to form a section 16, and is then folded upon itself

to form a section 17. At the opposite edge of the section 15 is a section 18, bent at an angle to section 15, and the metal then folded upon itself to form a section 19. The free 60 edge 20 of section 19 is preferably slightly curved or may be folded upon itself to provide a smooth finished edge adapted to slide freely over the face of the door or window frame.

As illustrated in Fig. 3, the parallel sections 16 and 17 are attached by a series of nails or screws 21 to a window frame 22, and where the joint between the frame 22 and the sash 23 is wide or loose, the weatherstrip occupies substantially the position shown in Fig. 3, with the section 18, pressed resiliently against the face of the sash 23, and the edge 20 of section 19 pressed resiliently against the face of the frame 22, 75 so as to effectually exclude wind and water. Where the joint between the sash 23 and frame 22 is close as shown in Fig. 4, the weatherstrip assumes substantially the position shown in Fig. 4, in which the section 18 80 is held resiliently against the face of the sash, the edge 20 of section 19 is held resiliently against the frame, and also the section 15 is bowed so that its curved central portion is held resiliently in contact with 85 the sash. In both positions 3 and 4 the section 17 is also held resiliently against the face of the frame 22 to a greater or less extent depending upon the extent to which the nails 21 permit the sections 16 and 90 17 to move relative to the frame, under the strain applied by the sash to sections 15 and 18. The weatherstrip is designed to be held substantially rigidly to the frame 22 at the point where the nails 95 are applied. Leverage is applied by the sash, tending to flex the weatherstrip from its original outline, at the extreme end of section 18 where such leverage would be most effective, and where the widest range of 100 movement would be capable of taking place. The resilient action of section 19 tends to counteract the action of leverage or force applied to the section 18, which results in the tension required to depress section 18 105 toward the frame 22 remaining substantially uniform for all positions, and at the same time no one of the yielding portions of the strip is strained to an extent which would tax its moment of resiliency 110 and cause it to take a permanent bend or set, hence the strip tends to perform its

functions and to retain substantially all of its resiliency for long periods of useful service.

In the modification Figs. 2, 6, 7, and 8 the section 30 corresponding to the section 15 of Fig. 1, is curved instead of plane. A section 31 corresponds to the section 16 of Fig. 1, and a section 32 corresponds to the section 17 of Fig. 1. The section 32 may be in one plane as illustrated in Fig. 1, or it may be bent to an obtuse angle as shown in Fig. 2, depending upon the amount of resiliency desired in the weatherstrip. A section 33 corresponds to the section 18 of Fig. 1, and a section 34 corresponds to the section 19 of Fig. 1. The section 34 is preferably curved or folded upon itself at 35 in order to provide a smooth edge adapted to readily slide along the face of the frame 36 in operation. As shown in Fig. 2 the section 34 is bent at an obtuse angle but may be all in one plane as shown in the section 19 of Fig. 1.

Fig. 6, illustrates substantially the position of the weatherstrip when applied to a loose joint between the window frame 36 and a window sash 37, and Fig. 7, illustrates substantially the position assumed by the strip Fig. 2, when applied to a close joint between the sash and frame. Fig. 8, illustrates a position of the parts intermediate of the positions shown in Figs. 6 and 7. It will be noted in Figs. 6 and 7 that due to the obtuse angle in the section 32 the middle portion of said section does not contact with the face 33 of the frame, and hence that the section 30 is given thereby increased resiliency where it joins the section 31, and hence is better able to apply uniform resistance to pressure from the sash, and to retain its resiliency for long periods of service. The obtuse angle in section 34 tends in like manner to increase the resiliency of the strip. The sections 17 and 19 of Fig. 1 are adapted to be bent to obtuse angles as shown in the corresponding sections 32 and 34 of Fig. 2, and for a like purpose.

In Fig. 5 I have illustrated a strip similar to Fig. 1, but with a section 170 corresponding to section 17 of Fig. 1, bent to an obtuse angle, similar to that shown at 32 of Fig. 2, and said strip applied to the joint between a door frame 40 and a door 41. In Fig. 9, I have illustrated at 60 the manner in which the weatherstrip is cut away or recessed opposite the door latch or lock bolt to enable the latch or bolt to enter its recess in the door frame, and it will be noted that such recess does not entirely sever the strip, and in fact does not materially reduce its strength. It will also be noted that the section 19 still functions to constitute a continuous wind and water proof joint, from top to bottom of the door irrespective of the latch and bolt or bolts.

Another important advantage of my in-

proved strip is that the section 17 or 32 where it extends past the edge of the section 16 or 31 serves to prevent the united edges of sections 16 and 17 or 31 and 32 from lifting or cocking away from the face of the frame 70 to which they are attached by the nails 21 at points intermediate of said nails and enables the nails to be spaced further apart. The curve in the sections 15 and 30 prevents buckling or bending of the strips and secures 75 superior contact with the opposite face of the joints.

The apparatus herein shown and described is capable of considerable modification within the scope of the claims without departing 80 from the spirit of my invention.

What I claim is:

1. A weatherstrip comprising a strip of resilient material folded longitudinally thereof face to face upon itself near opposite edges to form at opposite edges sections of double thickness, and separate leaf members extending inwardly from said double thick opposite edges of the main intermediate section at acute angles relative to said 90 double thick sections to independently contact with a joint face to constitute a wind and water proof joint.

2. A weatherstrip comprising a strip of resilient material folded longitudinally 95 thereof face to face upon itself to form a main intermediate section with double thick sections at opposite edges thereof, and two inwardly turned sections extending from the inner edges of said double thick sections and 100 at acute angles to said intermediate section, said strip being attached through one of its double thick sections to a first joint member and with the free edges of said inwardly turned sections resiliently in contact with 105 said first joint member to which its folded edge is attached, and with the opposite folded edge in yielding contact with the face of a second joint member.

3. A weatherstrip comprising a strip of 110 resilient material folded longitudinally thereof face to face upon itself to form a main intermediate section and double thick sections at opposite edges of said main section, and two inwardly turned sections each 115 diverging from a double thick section at an acute angle to the main intermediate section, said strip having contact with a first joint member at one double thick section and having contact with said first joint member at 120 the free edges of said diverging inwardly turned sections, and having resilient contact near the opposite double thick section with a second joint member.

4. A weatherstrip comprising in combination with first and second joint members, a strip of resilient material folded upon itself along one edge thereof to form an attaching section of double thick material by which the strip is attached to a first joint 130

member, said strip being transversely curved through its main or middle portion to present a convex face in contact with the face of the second joint member, and a terminal strip section turned inwardly at an acute angle from the free edge of said main strip section to secure resilient sliding contact at the free edge of said terminal strip section with the face of said first joint member to 10 which the strip is attached.

5. A weatherstrip comprising in combination with first and second joint members, a strip of resilient material folded upon itself along one edge thereof to form an attaching section of double thick material extending at an obtuse angle from the main strip section by which the strip is attached to a first joint member, a terminal strip section turned inwardly at an acute angle from the 20 free edge of said main strip and curved at its free edge to present a convex face in sliding engagement with said first joint member while the free edge of the main strip section maintains resilient engagement with the face of 25 the second joint member.

6. A weatherstrip comprising in combination with first and second joint members, a strip of resilient material folded longitudinally upon itself to form a main section and a relatively narrow terminal section turned inwardly upon and from one edge of said main section at an acute angle thereto and curved at its free edge, said main section being attached along its edge opposite to 30 said terminal section to a first joint member and with said main section extending at an obtuse angle from said first joint member toward and into contact with the second joint member, and with the convex curved 35 face of the free edge of said terminal section in yielding engagement with the face of said first joint member and with the free edge of the main section in yielding engagement 40 with the second joint member.

45 7. A weatherstrip comprising in combination with first and second joint members, a strip of resilient material folded longitudi-

nally upon itself to form an attaching section and a main section united at their meeting edges and at an obtuse angle one to the 50 other, a relatively narrow terminal section turned inwardly from the free edge of said main section at an acute angle thereto, said attaching section being attached to a first joint member and the free edge of said terminal section being in yielding engagement with said first joint member while the free edge of said main section is in yielding engagement with said second joint member, and a perforation through said main strip 60 section for the passage of a latch or bolt member.

8. A weatherstrip comprising in combination with first and second joint members, a strip of resilient material folded upon itself near its opposite edges in contact face to face to form a main section having a relatively narrow double thick section at each edge thereof, and a relatively narrow section of single thickness extending inwardly from the inner margin of one of said double thick sections across a portion of the width of the main section, the junction between said relatively narrow section and the inner margin 70 of the double thick section to which it is connected constituting a sharp obtuse angular bend in the material of the strip.

9. A weatherstrip comprising in combination with first and second joint members, a strip of resilient material folded upon itself in contact face to face, longitudinally to form at one edge a marginal section of double thick material, and a relatively narrow section of single thickness extending inwardly across a portion of the main section 80 from the inner margin of said double thick section, the junction between said relatively narrow section and the inner margin of said double thick section constituting a sharp obtuse angular bend in the material of the strip. 90

In testimony whereof, I have hereunto affixed my signature.

JAMES H. FOOTE.
